UNITED STATES PATENT OFFICE.

CHRISTIAN H. SMITH, OF TRAUGER, PENNSYLVANIA.

LATCH FOR MINE-CAR DOORS.

SPECIFICATION forming part of Letters Patent No. 752,265, dated February 16, 1904.

Application filed November 2, 1903. Serial No. 179,617. (No model.)

To all whom it may concern:

Be it known that I, CHRISTIAN H. SMITH, a citizen of the United States, residing at Trauger, in the county of Westmoreland and State of Pennsylvania, have invented a new and useful Latch for Mine-Car Doors, of which the following is a specification.

This invention relates to latches for mine-car doors.

10. The principal object of this invention is to provide a simple, durable, inexpensive, and useful latch for mine-car doors of such design that the weight of the load within the mine-car may by pressing against the door assist 15 in releasing the latch, so that the door may be opened and permit the contents of the car to be dumped.

A further object of the invention is to provide a simple and inexpensive latch for mine-car doors which will not be easily broken and which will be absolutely reliable in operation.

With the objects above mentioned and others in view, which will be readily seen as the invention is fully disclosed, the same consists 25 in the novel construction and combination of parts of a latch for mine-car doors hereinafter described, shown in the accompanying drawings illustrative thereof, and having the novel features thereof specifically pointed out in the 30 appended claims.

In the drawings, Figure 1 is an end elevation of a mine-car having the improved latch applied thereto. Fig. 2 is a detail view of the keeper by which the latch-operating lever is secured in position. Fig. 3 is a detail view of the keeper on the bottom of the car with which the end of the latch engages. Fig. 4 is a detail view of one of the clips in which the latch turns.

40. Referring to the drawings, in which corresponding parts are designated by similar characters of reference, C designates a mine-car provided in the end with a dumping-door D. The door D is preferably provided at the top 45 with a cross-bar 1, the ends of which project through bearings in the sides of the car and afford journals for the support of the swinging door. The door may be of any ordinary or preferred construction, being shown in the 50 present instance as comprising a plurality of

transverse boards 2, connected by vertical members 3, preferably of strap-iron of suitable strength, which are bolted or riveted to the boards.

The latch consists of a round bar 4, having 55 its lower end reduced slightly in diameter and bent to form a lateral projection 5. The bar 4 is rotatably supported in clips 6, preferably of the form shown in Fig. 4, and has a ring 7 secured on the bar near its upper end to 60 rest on the upper clip 6 and prevent the bar from sliding downward therethrough. At its upper end the bar 4 is slotted, as shown at 8, and a bent lever 9 is pivotally secured in the slot 8, as best seen in Fig. 1. The lever forms 65 the means for throwing the latch into operative position and is adapted for engagement with a keeper 10, attached to the mine-car door, as shown in Fig. 1. To limit the movement of the lever 9, a chain 11 is secured at one end 70 to the lever and has the other end secured to the door D of the car by a staple or other suitable fastening. The lateral projection 5 at the lower end of the latch-bar is adapted to engage with a keeper 12, rigidly fastened 75 to the bottom of the car and having an upturned end 13 of the form shown in Fig. 1, with which the projection 5 engages when the latch is in operative position. The upturned end 13 of the keeper 12 rises above the bottom 80 edge of the car-door, and in order to permit the car-door to swing outward when the latch is disengaged a notch 14 is formed in the bottom of the door at such a point that when the latch is released the car-door may swing outward and the end 13 of the keeper pass through the notch. When the latch is in the position shown in Fig. 1, with the lever 9 in engagement with the keeper 12, it will be seen that 85 turning of the latch-bar 4 in its bearings is 90 impossible and the vibration of the car in transit over the rails cannot dislodge the lever from the keeper. The pressure of the load within the car against the lower part of the door will of course force the lateral projection 95 5 of the latch-bar 4 into contact with the end 13 of the keeper 12, and the pressure exerted upon the latch will tend to rotate it in its bearings and will so press the lever 9 forcibly 100 against the keeper 12, thus preventing the le-

ver from resting loose in the space behind the keeper. When it is desired to release the latch in order to dump the contents of the car, the lever 9 may be easily raised above the top of the keeper 12, and as soon as the lever is no longer in engagement with the keeper the pressure of the load in the car against the door will suffice to turn the latch in its bearing-clips and permit the door to swing outward.

From the foregoing description and the drawings illustrative thereof it will be noted that the construction of the latch is extremely simple, that the amount of material used there-
is small, and that the parts are so arranged and designed that sufficient strength is possessed by all the parts upon which the strain falls, so that the possibility of breakage is reduced to a minimum.

When it is desired to close the mine-car and secure it by means of the latch after the load has been dumped, the door must be swung inward until the bottom thereof has passed over the upturned end 13 of the keeper 12. The latch-bar 4 will then be turned in its bearings by means of the lever 9 until the lever can enter the space behind the keeper, when the lever will be forced down into engagement with the keeper and the latch secured in operative position.

While the invention has been described and illustrated in the preferred form of embodiment thereof, it is obvious that various changes in the form, proportions, and exact mode of assemblage of the elements may be resorted to without departing from the spirit of the invention or sacrificing any of its advantages, and I do not limit myself to the exact form and arrangement of the elements shown and described.

Having thus described the construction and operation of my invention, what I claim as new, and desire to secure by Letters Patent, is—

1. The combination with a door, of a latch-bar arranged for rotation on said door and having a lateral projection, a keeper adapted for engagement by said lateral projection, a lever on said latch-bar, and means mounted on the door for engagement by said lever to hold the latch in operative position.

2. The combination with a horizontally-pivoted mine-car door, of a rotatable latch-bar

vertically arranged thereon and having a lateral projection, a keeper on the car adapted for engagement with said lateral projection, 55 a lever attached to the latch-bar, and means on the car-door to engage with said lever and hold the latch in operative position.

3. The combination in a device of the class described, of a rotatable latch-bar having a 60 lateral projection on one side thereof and a lever arranged at the opposite side, a keeper for engagement with said lateral projection when the latch is in operative position, and means for engagement with the lever to hold 65 the latch in operative position.

4. The combination with a horizontally-pivoted mine-car door, of a rotatable latch-bar vertically arranged thereon and having a lateral projection at its lower end, a keeper mounted on the bottom of the car and adapted to be engaged by said lateral projection when the latch is in operative position, a lever attached to said latch-bar and extending therefrom on the side opposite said lateral projection, and a 75 keeper on the door to secure said lever when the latch is in operative position.

5. The combination with a horizontally-pivoted mine-car door, of a rotatable latch-bar vertically mounted thereon, said latch-bar having 80 a lateral projection at the lower end adapted to swing under the door, a keeper on the bottom of the car for engagement with said lateral projection when the latch is in operative position, a lever attached to said latch-bar, 85 and means for engagement with said lever to hold the latch in operative position.

6. The combination with a horizontally-pivoted mine-car door, of a rotatable latch-bar vertically disposed thereon and having a lateral 90 projection, a keeper mounted on the car for engagement with said lateral projection when the latch is in operative position, a pivoted lever mounted in the upper end of said latch-bar, and a keeper on the car-door for engagement with said lever to hold the latch in operative position.

In testimony that I claim the foregoing as my own I have hereto affixed my signature in the presence of two witnesses.

CHRISTIAN H. SMITH.
